UNITED STATES PATENT OFFICE.

ANDREW EPPLER, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE-SEWING MACHINE.

1,339,645.

Specification of Letters Patent. Patented May 11, 1920.

Application filed April 22, 1916. Serial No. 92,854.

To all whom it may concern:

Be it known that I, ANDREW EPPLER, a citizen of the United States, residing at Lynn, in the county of Essex and State of Massachusetts, have invented certain new and useful Improvements in Shoe-Sewing Machines; and I do hereby declare the following to be a full, clear, and exact description of the invention, such as will enable others skilled in the art to which it appertains to make and use the same.

The present invention relates to shoe sewing machines, and more particularly to curved needle sewing machines adapted for stitching a welt to a stitch down shoe.

An object of the present invention is to provide a sewing machine by which a welt may be attached in an inverted position in the angle formed by the out turned flange 20 of the upper of a stitch down shoe so that the welt may be folded down upon the out-turned flange to cover the welt attaching seam.

In accordance with this object one feature 25 of the invention contemplates the provision, in a shoe sewing machine provided with a presser foot and a work support adapted to clamp the projecting edge of a shoe sole between them, of a welt guide adapted to 30 hold an inverted welt during the sewing operation in position to be subsequently folded away from the shoe over the attaching seam and upon the projecting sole edge. In the preferred embodiment of this feature of the invention the welt guide has, 35 angularly arranged guiding faces to fold the welt into an angular shape and the welt guide is arranged to place the apex of the angle formed by the welt approximately 40 in the line of the seam formed by the machine.

The machine hereinafter specifically described as embodying the preferred form of the present invention is provided with a 45 presser foot which reciprocates in the line of feed with the awl during the feeding movement of the shoe. The welt guide is formed in the presser foot and on the return stroke of the presser foot the welt is 50 pulled through the guide. The presser foot is fixed against vertical movement and the work is intermittently clamped against it by a vertically movable work support. During the return stroke of the presser foot the

needle is in the work and in order to relieve 55 the strain which would otherwise be placed upon the needle and tend to bend it out of alignment, the machine is provided with means for depressing the work support during the return movement of the presser foot. 60 This machine, in addition to the feature of invention above referred to, also embodies certain novel features of construction and operation hereinafter described and claimed, the advantages of which will be obvious to 65 those skilled in the art.

The various features of the invention are illustrated in the accompanying drawings in which Figure 1 is a view in front elevation of a shoe sewing machine embodying 70 the preferred form of the invention; Fig. 2 is a view in side elevation with parts broken away, of the machine shown in Fig. 1; Fig. 3 is a sectional plan view showing the work support locking devices; Fig. 4 is 75 a detail view in side elevation showing the feed slide and presser foot adjusting mechanism; Fig. 5 is a detail view in vertical section showing the releasing lever for releasing the pawls from the work support 80 locking device; and Fig. 6 is a vertical section of a stitch down shoe illustrating the manner in which a welt is attached to the shoe by the sewing machine illustrated in the other figures. 85

The sewing machine illustrated in the drawings is a curved hooked needle wax thread shoe sewing machine having substantially the same construction and operation of parts as the machine illustrated 90 and described in the patent to Eppler, No. 1,030,880, patented July 2, 1912. This machine is provided with an awl 10, needle 12, looper 14, thread finger 16, take-up 18, presser foot 20, and work support 22 which 95 operate in the usual manner to form a chain stitch.

The awl 10 is mounted upon a feed slide 24 which slides in guideways 26 formed on the machine frame, Figs. 1, 2 and 4. The feed slide is reciprocated by a lever 28 pivotally mounted upon a stud 30 in a stationary part of the machine frame and carrying at its lower end a cam roll 32 which engages a slot 34 in the face of a cam 36. The lever 105 28 is slotted at 38 to receive a pivot pin 40 in a block 42 which is adjustably connected with the slide 24 by means of slots 44 and

bolts 46. The presser foot 20 is mounted upon a slide block 48 which works in a dove-tailed slot 50 formed in the feed slide 24. The outer end of the presser foot has a 5 gage face 52, Fig. 2, which is adapted to engage the upper and determine the position of the seam in the work. This gage face may be adjusted toward and from the work to vary the position of the seam by means 10 of a hand lever 54 which is fixed on a shaft 56 mounted in the feed slide 24. The hand lever 54 is connected with the presser foot slide block by means of a gear 58 mounted upon the shaft 56 and a gear 60 interposed 15 between the gear 58 and a rack 62 formed on the upper side of the slide 48. The upper end of the hand lever 54 is provided with a boss 65 which moves between adjusting screws 66 to determine the position of the 20 seam. The adjusted position of the presser foot is maintained by means of a clamp 68 which is mounted upon the feed slide 24 and engages the slide block 48. With the construction outlined above the presser foot reciprocates in the line of feed with the awl and is adjustable transverse to the line of feed. The work engaging face of the 25 presser foot remains in the same plane and is normally stationary to act as an abutment 30 against which the work is clamped during a portion of the sewing operation.

The work support 22 is mounted upon a carrier 70, Figs. 1 and 2, which is pivotally mounted on the machine frame by parallel 35 links 72 and 74. The effective swinging radii of the links 72 and 74 move the face of the work support 22 substantially in an arc concentric to the axis of the needle so that the work is always correctly positioned 40 on the support with relation to the needle. The work support is moved into yielding engagement with the work by means of a spring 45 76 which is connected between a locking plunger 78 and an eye bolt 80 adjustably mounted in the machine frame. The locking plunger 78 is slidably mounted in brackets 82 attached to the machine frame and the front end of the plunger is pivoted to a block 84 which is slidably mounted in a guideway 86 50 formed on the rear end of the work support carrier link 74, Figs. 2 and 3. As the work support is forced up by the spring 76, it is locked in clamping position by four pawls 88 which engage a ratchet plate 90 mounted 55 upon the plunger 78. The pawls 88 are mounted on the machine frame opposite the plate 90 and are spaced with relation to the teeth on the plate 90 so that the plunger will be locked in practically any position. 60 Each pawl is independently held in engagement with the ratchet plate by means of a series of leaf springs 92.

Periodically in the operation of the stitch forming mechanism the plunger 78 is unlocked to release the work support from a 65

rigid clamping position, thus facilitating the feeding of the work. To unlock the plunger 78 the pawls are released from the ratchet plate 90 by a cam 94 which actuates a releasing lever 96. The releasing lever is 70 pivoted to the machine frame and has a dog 98 arranged to engage recesses 100 formed in the pawls 88. The upper end of the lever 96 is provided with a screw 102 which engages the forward end of a cam lever 104 75 pivoted to the machine frame directly below the cam 94. The rear of the cam lever carries a roll 106 which projects into a cam path in the face of the cam 94. The releasing lever 96 is connected by means of a spring 108 to the cam lever, the spring acting to normally hold the lever 96 up, so as to permit the leaf springs 92 to force the pawls 88 into engagement with the ratchet plate 90. When the cam lever 104 is not acting to release the pawls from the ratchet, it is held in a position by the cam 94 to draw the releasing lever 96 upward by means of the spring 108, and free the pawls for engagement with the ratchet plate 90. The releasing lever 96 has a handle 110 by which it may be manually operated to remove the pawls 88 from the ratchet and unlock the plunger at any time. When the plunger is unlocked, the work support is yieldingly held against the work by the spring 76 and 80 may be drawn down away from the presser foot by means of a treadle (not shown). The treadle is connected by means of a rod 112 with a hook 114 formed on the forward end of the carrier link 74. While the machine is stopped, the work support may be unlocked by withdrawing the needle and awl from the work and the work support may be drawn down by the foot treadle to enter and 85 remove the work. If at any time during the sewing operation, however, the operative desires to remove or adjust the work, the work support may be manually unlocked by the lever 96 and drawn down away from the work by the foot treadle. The parts described above are substantially the same in their construction and mode of operation as the parts described in the patent above referred to and reference is hereby made to 90 said patent for a detailed description of these parts.

The stitch down shoe illustrated in Fig. 6 is made by attaching the out-turned flange 116 of an upper 118 to an insole 120 by a 95 dry thread seam 122. After the upper has been attached to the insole it is placed upon a last 124. A welt 128 is then secured in inverted position in the angle between the upper and out-turned flange by means of a 100 seam 130 which passes through the insole 120, out-turned flange 116, and the welt 128. After the welt has been sewed to the insole and upper an outsole is positioned upon the insole 120 and the portion of the welt which 105

engages the upper is turned down upon the out-turned flange 116 to cover the seam 130 and dry thread seam 122. The welt is fastened upon the out-turned flange by an out-seam 132 which passes through the outsole, insole, out-turned flange, and welt, as shown on the right side of the shoe in Fig. 6.

To properly shape the welt to fit into the angle formed by the upper and out-turned flange a welt guide is formed in the presser foot of the sewing machine which has welt guiding slots to bend the welt into an angular shape and position it in an inverted position upon the upper so that the seam will be laid approximately in the angle formed in the welt. To this end, welt guiding slots 134 and 136 are formed in the presser foot 20 directly behind the gage face 52 of the welt. The guiding slots 134 and 136 have 25 an angular relation, and as the welt passes through them the portion of the welt passing through the slot 136 is positioned upon the out-turned flange 116 and the portion passing through the guiding face 134 is positioned against the upper 118. The presser foot positions the seam approximately in the angle formed by the upper and the out-turned flange, and the welt is positioned so that the seam passes through the apex of the 30 angle of the welt formed by the guiding slots. In this way the welt will be securely fastened in the angle formed by the upper and out-turned flange, and when the welt is turned down upon the out-turned flange the 35 welt attaching seam will be covered. The presser foot is adjustable transversely to the shoe in varying the position of the seam, and since the welt guiding slot is formed in the presser foot it will be adjusted with the 40 presser foot and carry the welt transversely to the shoe to position it in the line of the seam.

The presser foot and the welt guide reciprocate in the line of feed of the work 45 and during their return stroke the welt is drawn through the guiding slots in the presser foot. The needle is in the work to hold it during the return stroke of the presser foot. In order to minimize the 50 strain on the needle, the work support is positively withdrawn from the presser foot to remove the drag of the presser foot upon the work during the return stroke. To accomplish this, the cam 94 for releasing the 55 work support locking devices is designed to release the work support during the return movement of the presser foot. At this time the work support is positively drawn down from the presser foot against the tension of the spring 76 by means of a path cam 138. The cam 138 is connected with the work support by means of a bellcrank 140 which is pivoted to a stationary part of the machine frame. One arm of the bell- 60 crank lever engages an adjusting screw 142

mounted in an arm 144 formed on the carrier link 72, and the other arm of the bellcrank lever carries a roll 146 which works in the path cam 138. With this construction the work support is positively withdrawn to free the work during the return movement of the presser foot. 70

The preferred form of the invention having been thus described, what is claimed is:—

1. A shoe sewing machine, having in combination, a yieldingly mounted work support, a presser foot fixed against vertical movement coöperating therewith to clamp the projecting edge of a shoe sole, means 80 for imparting feed and return movements to the presser foot during each cycle of operations of the machine, and means acting during each cycle of operations of the machine for depressing the work support during the return movements of the presser foot.

2. A shoe sewing machine, having in combination, stitch forming devices, a yieldingly mounted work support, a presser foot 90 fixed against vertical movement coöperating therewith to clamp the edge of a shoe sole, means for imparting feed and return movements to the presser foot during each cycle of operations of the machine, means for 95 locking and unlocking the work support during each cycle of operations of the machine, and means acting during each cycle of operations of the machine for depressing the work support during the return movements of the presser foot.

3. A shoe sewing machine, having in combination, stitch forming devices including a needle, a presser foot provided with a welt guide, a work support coöperating with the 105 presser foot to clamp the projecting edge of a shoe sole, and means for imparting feed movements to the presser foot while the needle is out of the work and return movements while the needle is in the 110 work.

4. A shoe sewing machine, having in combination, stitch forming devices including a needle, a presser foot provided with a welt guide, a work support coöperating with the 115 presser foot to clamp the projecting edge of a shoe sole, means for imparting feed movements to the presser foot while the needle is out of the work and return movements while the needle is in the work, and 120 means for separating the work support and presser foot during the return movements of the presser foot.

5. A shoe sewing machine, having in combination, stitch forming devices, a yieldingly mounted work support arranged to support the projecting edge of a shoe sole, a presser foot coöperating therewith fixed against vertical movement and provided 125 with a welt guide, means for imparting feed 130

and return movements to the presser foot during each cycle of operations of the machine, and means for depressing the work support during the return movements of the presser foot.

6. A shoe sewing machine, having in combination, stitch forming devices, a presser foot provided with a welt guide, comprising angularly disposed guiding slots to fold the welt into an angular shape and arranged to place the apex of the angle of the welt approximately in the line of the seam, and a work support coöperating with the presser

foot to clamp the projecting edge of a shoe sole.

7. A shoe sewing machine, having in combination, stitch forming devices, a work support arranged to support the projecting edge of a shoe sole, and a presser foot co-operating therewith provided with a welt guide arranged to hold an inverted welt during the sewing operation in position to be subsequently folded away from the shoe over the attaching seam and upon the projecting sole edge.

ANDREW EPPLER.
